UNITED STATES PATENT OFFICE.

WILLIAM A. BUCKNER, OF FRESNO, CALIFORNIA.

SPRINKLER.

Application filed February 20, 1926. Serial No. 89,633.

This invention relates to improvements in the irrigating art and particularly with sprinklers used in connection with portable, underground and overhead and like irrigating systems for all purposes.

In a sprinkler used in these types of irrigating systems, it is essential that as large a radius of distribution of the water as possible be had from the stand pipe, and also it is imperative that there be an even distribution of the water for the entire radius covered in order to most economically and efficiently carry out the irrigating processes.

To this end it has ordinarily been the practice to provide a sprinkler with one or more outlet nozzles arranged to produce as great a throw as possible and to cover the complete circle of movement, means being provided to slowly rotate the sprinkler; the slower the rotation the more efficiently the water is distributed. Heretofore, however, this mechanism has been more or less complicated and costly to operate and maintain. It is the object of the present invention therefore to produce a sprinkler which is simple, cheap and durable and which will cover as great or greater an area than any of the costly and complicated sprinklers now commonly in use, and one which will reduce the cost of overhead installation to a minimum and yet give better results than the other sprinklers noted.

These objects I accomplish by means of such structure and relative arrangement of parts as will fully appear by a perusal of the following specification and claims.

In the drawings similar characters of reference indicate corresponding parts in the several views:

Fig. 1 is a side elevation partly broken out and in section of my improved sprinkler.

Fig. 2 is a top plan view of the same.

Referring now more particularly to the characters of reference on the drawings, the numeral 1 designates the base coupling arranged for connection with the stand pipe and provided with a swivel cup 2 in its upper end. The numeral 3 designates the swivel or rotating pipe of the sprinkler head which projects into the swivel cup 2 and is provided at its lower end with an annular flange 4 to seat against the bottom of the cup 2. A swivel plug 5 screws into the cup 2, and there is a washer 6 of leather or the like interposed between the flange 4 and the plug 5 so that when the sprinkler

head is under the pressure of the water passing therethrough there is no metal to metal bearings, and a perfectly tight joint is assured to prevent the ingress of dirt or the like and the egress of water.

The swivel plug 5 is in the form of a short cylindrical body which fits closely around the pipe 3 for the full length of said pipe so as to form an extending bearing for the pipe and thus prevent it from canting or binding with the rotation of the sprinkler head.

At the upper end of the pipe 3 is the coupling head 7 connected with which is the primary outlet nozzle pipe 8 connected into the coupling 7 in direct central alinement with the vertical axis thereof. The pipe 8 is bent at a substantial angle of 30 degrees from the vertical, and provided with the discharge nozzle 9 at its outer end. The numeral 10 designates the secondary discharge nozzle pipe which connects into the head 7 at substantially right angles thereto, and is provided at its outer end with a discharge nozzle 11 mounted adjacent which is a bracket 12 having a projecting arm 13, on the outer end of which is a bearing sleeve 14. A small shaft 15 projects through the bearing sleeve 14 and on one end thereof is mounted a small propeller 16 similar to an aeroplane propeller in shape, and on the opposite end of the shaft 15 is a small overshot water wheel 17 mounted in the path of the water to be discharged through the nozzle 11. The blades or paddles of the water wheel 17 have quite an abrupt bevel as at 18, so as to scatter the water discharged thereagainst in a well distributed manner and also to set up a vibration relative to the entire sprinkler head.

In practice the water from the stand pipe discharges in a direct uninterrupted stream through the swivel joint and into the nozzle pipe 8 and out the nozzle 9. This discharges the water to the outside periphery of the complete radius of the area to be irrigated. The water passing through the pipe 10 and nozzle 11 is diffused by the rotation of the water wheel 17 and the propeller 16 so as to thoroughly distribute it inside of the circle around the stand pipe. With the parts positioned as shown in Fig. 2 there will be a reactive effect exerted by the issuing water on the nozzle 11, tending to move the arm 10 in a clockwise direction. The impact of the stream against the blades 18, however, will to some small extent neutralize this re-

active effect. However, the driving of the propeller through the action of the wheel 17 will co-operate with the re-active effect of the issuing stream to drive the arm 10 and connected parts in a clockwise direction. The vibration set up by the impact of the water against the wheel 17 keeps the rotating head from binding in its bearings under the pressure of the water thereagainst and thus 10 facilitates the rotating action. The speed of rotation is controlled by the angle at which the secondary nozzle is placed. The farther it is placed to the left the greater will be the speed of rotation of the sprinkler 15 head in a clock-wise manner and vice versa as it is turned to the right the speed will be slowed down.

It will be seen from the description of the foregoing sprinkler that while it is very 20 simple and inexpensive to manufacture, maintain and operate nevertheless it is capable of performing the full functions for which a sprinkler of this type is designed, namely; to throw the water to the greatest 25 possible radius and to thoroughly discharge it over the entire area to be irrigated, doing all that the more expensive, complicated sprinklers now on the market can be expected to do.

30 From the foregoing description it will be readily seen that I have produced such a device as substantially fulfills the objects of the invention as set forth herein.

While this specification sets forth in detail 35 the present and preferred construction of the device, still in practice such deviations from such detail may be resorted to as do not form a departure from the spirit of the invention, as defined by the appended claims.

40 Having thus described my invention what I claim as new and useful and desire to secure by Letters Patent is:

1. A sprinkler comprising a rotatable head, discharge nozzles arranged on the head, a propeller supported by the head, the propeller having a horizontal axis set at a tangent to an imaginary circle having as its center a point in the vertical axis of the

head, and means to impart rotation to the propeller whereby the action of the same 50 against the air will tend to rotate the head.

2. A sprinkler comprising a rotatable head including a primary discharge nozzle, a pipe projecting from the head at an angle to the primary discharge nozzle and having a secondary discharge nozzle at its outer end, 55 a propeller journaled at the end of the projecting pipe, the propeller having a horizontal axis set at a tangent to an imaginary circle having as its center a point in the vertical axis of the head, and means for driving the propeller whereby the action of the propeller on the air will tend to rotate the head.

3. A sprinkler comprising a rotatable head 60 including a primary discharge nozzle, a pipe projecting from the head at an angle to the primary discharge nozzle and having a secondary discharge nozzle at its outer end, a propeller journaled at the end of the projecting pipe, the propeller having a horizontal axis set at a tangent to an imaginary circle having as its center a point in the vertical axis of the head, and means for driving 65 the propeller through the medium of the issuing stream of water from the secondary nozzle, whereby the action of the propeller on the air will tend to rotate the head.

4. A sprinkler comprising a rotatable head including a primary discharge nozzle, 70 a pipe projecting from the head at an angle to the primary discharge nozzle and having a secondary discharge nozzle at its outer end, a bracket fixed at the outer end of the pipe, a horizontal shaft journaled in the bracket 75 at a tangent to an imaginary circle having as its center a point in the vertical axis of the head, an overshot water wheel fixed to one end of the shaft, and a propeller fixed to the opposite end of the shaft, the secondary 80 nozzle being arranged to discharge water against the water wheel to drive the propeller shaft.

In testimony whereof I affix my signature.

WILLIAM A. BUCKNER.
